UNITED STATES PATENT OFFICE.

ROBERT M. KEATING, OF SPRINGFIELD, MASSACHUSETTS.

WHEEL-RIM.

1,207,927

Specification of Letters Patent. Patented Dec. 12, 1916.

Application filed February 27, 1914. Serial No. 821,527.

To all whom it may concern:

Be it known that I, ROBERT M. KEATING, a citizen of the United States of America, residing at Springfield, in the county of 5 Hampden and State of Massachusetts, have invented a new and useful Wheel-Rim, of which the following is a specification.

My invention relates to improvements in pneumatic-tire rims, which are more especially designed for wire wheels, and consists of a flanged band provided with one or more interior reinforcing ribs, with which may be used a flanged ring adapted to be fastened to said band, and provided with a receiving 15 shoulder for one of the band ribs, all as hereinafter set forth.

The object of my invention is to produce a rim that is light both in weight and stock, while at the same time it is strong and durable, and sufficiently stiff and rigid to render the same especially well adapted for use in the manufacture of so-called wire wheels.

A further object is to provide such a rim with convenient and efficient means for attaching to or mounting thereon a tire, and for detaching from or dismounting such tire.

In this construction ample provision is made for resistance to all strain to which a 30 wheel and its rim are liable under ordinary conditions of use, so that there is practically no liability of peripheral fracture, or of yielding under lateral stress, or of having its detachable member broken or wrenched 35 out of place.

Other objects and advantages will appear in the course of the following description.

I attain the objects and secure the advantages of my invention by the means illustrated in the accompanying drawings, in which—

Figure 1 is a side elevation of one-half of a wheel rim which embodies a practical form of my invention, such elevation being an inside edge view, or a view of the edge of the rim that comes next to the vehicle body; Fig. 2, a cross-section through such rim, taken on lines 2—2, looking in the direction of the associated arrow, in Fig. 1; Fig. 3, a 45 fragmentary cross-section, on lines 3—3, looking in the direction of the associated arrow, Fig. 1; Fig. 4, a cross-section showing a rim construction in which no ring is necessary; Fig. 5, a sectional 50 detail illustrating modified fastening means, and, Fig. 6, a similar view of still another modification.

Similar numerals designate similar parts throughout the several views.

This rim usually comprises a band 1 and a 60 ring 4, the latter being attached to the former by means of a series of bolts 5. The band 1, at what may be termed the inner edge, because it is the edge that is next to the body of the vehicle, when a wheel of 65 which said band forms a part is in place, is turned outwardly beyond the periphery of said band to form a tire flange 6 of ordinary shape and structure. The band 1 is preferably provided on the inside, at or adjacent 70 to the junction of the flange 6 with the band proper, with an annular strengthening and stiffening rib 7, and said band is further provided on the inside, at or adjacent to the edge thereof which is opposite to the edge 75 from which said flange extends, or the outer edge, with a second strengthening and stiffening rib 8. In the present construction, the outer edge of the band 1 is bent inwardly to form the rib 8. The outer ends of the 80 wheel spokes are attached to the band 1, but since such spokes and the attaching means therefor form no part of this invention the same are not herein shown.

The ring 4 has a tire flange 9 to correspond with the flange 6 on the band 1 and coöperate with the latter flange in holding a tire in place on said band. An annular shoulder 10 is provided on the inner face of the ring 4 to fit into the space within the 85 inner edge of the rib 8, and to receive said rib and enable said ring to bear against the outer edge of the band 1 and the outside of said rib. Thus the ring 4 is carried or supported on the rib 8, whereby the bolts 5 are 90 protected from much if not all shearing or lateral strain and their only office is to retain said ring in place against the band 1 and such rib, and assist in counteracting any independent rotary tendency that the ring 95 might have imparted to it. The ring 4, by being mounted in this manner on and in the band 8, also adds to the strength, stiffness and stability of the band and of the rim as a whole. Each bolt 5 passes from the outside through an opening in the ring 4 and an opening in a lug 11 in the band 1, which lug opening is tapped to receive such bolt. The lugs 11 are on the inside of the rib 8, 100 and are usually located in the angle which 105

55 detail illustrating modified fastening means, 110

said rib forms with the band 1, so that said rib forms the outer ends of such lugs and said band forms the outer sides thereof.

In practice, while the ring 4 is off, a tire 5 is mounted on the band 1, and then said ring is placed in position and the bolts 5 are inserted in the openings provided to receive them and screwed into the lugs 11 until said ring is forced tightly against said band and 10 the rib 8, by the heads of said bolts. A tire thus mounted is held securely on the band 1 by the flanges 6 and 9. The removal of a tire is effected by unscrewing the bolts 5, taking away the ring 4, and withdrawing 15 the tire from the band 1.

A single-piece rim is shown in Fig. 4. This rim consists of a band 12 having tire flanges 6—6, and interior reinforcing ribs 13—13, the latter in this case being produced 20 by bending the metal out of which the rim is constructed. The ribs 13 might be substituted for the ribs 7 and 8, and vice versa. The Fig. 4 rim is old except for the addition of the reinforcing ribs, but this addition is 25 a new feature in rim construction, which makes it possible and practicable to use in a wire wheel a rim of the otherwise old type. The lugs 11 for the bolts 5 may be omitted and such bolts may be tapped into the flange 30 8, or one of the modifications shown in the last two views can be resorted to. The first of these modifications (Fig. 5) shows a bolt 14 inserted in the rib 8, from the inside, and passed through said rib and the ring 4, to 35 receive a nut 15 on its outer end, a part of the head of said bolt being cut off to provide

bearing parts which engage the band 1, as represented at 16, to prevent said bolt from turning. In the second modification in question (Fig. 6), a headed sleeve 17 is inserted 40 in the rib 8 and ring 4, from the inside of said rib. The sleeve 17 is tapped to receive a bolt 18 from the outside of the ring 4, the head of said sleeve being fitted to the band 1, like the head of the bolt 14, to prevent 45 said sleeve from turning.

Such changes in the shape, size, arrangement, and construction of the rim, as may be required to meet different conditions, and in addition to those specifically pointed out 50 and illustrated, may be made, without departing from the spirit of my invention, provided the scope of my claim be not exceeded.

What I claim as my invention, and desire to secure by Letters Patent, is—
55

The combination, in a wheel rim, with a band having a tire-engaging part, and provided with internal annular ribs, one of such ribs being located adjacent to the outer edge of said band, and said band being further provided with bolt-receiving lugs located inside of the outer rib, of a ring having a tire-engaging part, and provided with an annular shoulder to receive and fit within 60 said outer rib, and bolts adapted to pass through said ring into said lugs, to secure 65 said ring to said band.

ROBERT M. KEATING.
